US00D875824S

(12) United States Design Patent (10) Patent No.: US D875,824 S
Barlier et al. (45) Date of Patent: * Feb. 18, 2020

(54) TYPE FONT

(71) Applicant: Apple Inc., Cupertino, CA (US)

(72) Inventors: Guillaume P. Barlier, San Mateo, CA (US); Aurelio Guzmán, San Jose, CA (US); Nicolas V. Scapel, Sunnyvale, CA (US); Christopher Wilson, San Francisco, CA (US)

(73) Assignee: Apple Inc., Cupertino, CA (US)

() Term: 15 Years

(21) Appl. No.: 29/684,046

(22) Filed: Mar. 18, 2019

Related U.S. Application Data

(63) Continuation of application No. 29/616,905, filed on Sep. 10, 2017, now Pat. No. Des. 843,442.

(51) LOC (12) Cl. 18-03

(52) U.S. Cl. USPC D18/27

(58) Field of Classification Search

USPC D18/24, 29, 30, 31, 32, 33; D14/485, D14/486, 487, 488, 489, 490, 491, 492, D14/493, 494, 495; 715/752

CPC B41B 1/02; G06F 3/4817

See application file for complete search history.

(57) CLAIM

The ornamental design for a type font, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a face view of a type font showing the claimed design; and,

FIG. 2 is a second embodiment thereof.

1 Claim, 2 Drawing Sheets
